(57) CLAIM

The ornamental design for a disinfectant dispenser, as shown and described.

DESCRIPTION

1. Disinfectant dispenser
2. Disinfectant dispenser
3. Disinfectant dispenser
4. Disinfectant dispenser
5. Disinfectant dispenser
6. Disinfectant dispenser
7. Disinfectant dispenser
8. Disinfectant dispenser
9. Disinfectant dispenser
10. Disinfectant dispenser
11. Disinfectant dispenser
12. Disinfectant dispenser
